UNITED STATES PATENT OFFICE.

JACOB FRANK, OF PHILADELPHIA, PENNSYLVANIA, ASSIGNOR OF ONE-HALF
TO JOHN FRANK, OF SAME PLACE.

DESIGN FOR A CAP.

SPECIFICATION forming part of Design No. 26,533, dated January 12, 1897.

Application filed December 9, 1896. Serial No. 615,059. Term of patent 3½ years.

To all whom it may concern:

Be it known that I, JACOB FRANK, a subject of the Czar of Russia, residing in the city and county of Philadelphia, State of Pennsylvania, have invented and produced a new and original Design for Children's Caps, of which the following is a specification, reference being had to the accompanying drawings, forming a part thereof.

- The leading feature of my design for a cap is the rim of the same with ornamentations thereon.

Figure 1 represents a perspective view of a

cap embodying my design. Fig. 2 represents a vertical section thereof.

Referring to the drawings, A designates a cap consisting of the body B and the rim C. On the rim are geometrically-shaped figures D and the rosette E.

What I claim is—

The design for a cap substantially as described and shown.

JACOB FRANK.
